The ornamental design for lighting fixture, as shown and described.

DESCRIPTION

FIG. 1 is a perspective view of a lighting fixture of the design of the present invention;

FIG. 2 is a top view thereof;

FIG. 3 is a bottom view thereof;

FIG. 4 is a right side view thereof; the left side view being the same; and,

FIG. 5 is a front view thereof; the back view being the same. Those portions of the present invention which are presented in phantom lines illustrate the environment of the design only and form no part of the claimed design. Moreover, the shading presented in the accompanying drawings is provided merely to highlight the contour of the invention and is not intended to be illustrative of texture or gloss.
